UNITED STATES PATENT OFFICE.

ISAAC MASON, OF NEW YORK, N. Y.

CONVERTIBLE COUCH AND BED.

993,856.

Specification of Letters Patent. Patented May 30, 1911.

Application filed September 1, 1910. Serial No. 579,986.

To all whom it may concern:

Be it known that I, ISAAC MASON, a citizen of the United States, and a resident of the city of New York, borough of Brooklyn, in the county of Kings and State of New York, have invented a new and Improved Convertible Couch and Bed, of which the following is a full, clear, and exact description.

10 The invention relates to household furniture, and its object is to provide a new and improved convertible couch and bed, arranged to permit quick and convenient converting of the piece of furniture from a couch to a double bed and vice versa, and to accommodate the bedclothes when using the piece of furniture as a couch. For the purpose mentioned, use is made of a frame consisting of a head section, a middle section 15 and a foot section, of which the head and foot sections are slideable lengthwise on the middle section, the head section having a fixed head and the foot section having movable members capable of forming the ends 20 of the couch or the foot of the bed.

A practical embodiment of the invention is represented in the accompanying drawings forming a part of this specification, in which similar characters of reference indicate corresponding parts in all the views.

Figure 1 is a perspective view of the piece of furniture folded to form a couch; Fig. 2 is a similar view of the same extended to form a bed; Fig. 3 is a sectional side elevation of the couch with the upholstery omitted; Fig. 4 is a cross section of the same on the line 4—4 of Fig. 3; Fig. 5 is a longitudinal section of the bed with the mattress and bedclothes omitted; and Fig. 6 is a perspective view of the convertible mattress section and pillow.

The frame for the couch and bed is made in three sections, A, B and C, of which A is the head section, B the middle section and C the foot section. The bed spring is likewise made in three parts D, D', D'', of which the end sections D and D'' are pivotally connected with the middle section D' by pivots D³ and D⁴, and the middle section is connected at the pivots D⁴ with the sides B' of the middle frame section B.

The upholstery for the couch and mattress of the bed is made in sections E, E', and a double section E'', made in the form 55 of a bag open at one end to contain a pillow or cushion E³, as indicated in Fig. 6. When

the piece of furniture is used as a bed, the section E fits and rests on the bed spring section D, the section E' fits and rests on the bed spring section D', and the two sections 60 E² fit and rest on the bed spring section D''. When the piece of furniture is used as a couch, the section E forms the upholstered back of the couch, as indicated in Fig. 1, while the section E' is the seat, and the 65 pillows E³ are used loosely on the couch, as indicated in Fig. 1.

The middle section B of the frame has its sides B' connected with each other by a box B², for storing bedclothes and the like 70 when using the piece of furniture as a couch, and the sides B' of the said middle section are provided with two sets of longitudinal guideways B³, B⁴, of which the guideways B³ are slidably engaged by the sides A' of 75 the head section A, and which sides A' are rigidly connected with each other by a head piece A². The set of guideways B⁴ is slidably engaged by side bars C' of the foot section C of the frame, so that the head section A and the foot section C can be moved toward and from each other when folding or extending the parts to form the couch and the bed, respectively, as will be readily understood by reference to the drawings. The 80 bars C' of the foot section C are rigidly connected with each other by a cross piece C² having corner posts C³ adapted to rest on the floor.

The free end of the bed spring D is provided with a cross rail D⁵ adapted to engage a keeper F held on the head piece A² of the head section A, and the free end of the bed spring section D'' is provided with a cross rail D⁶ adapted to engage keepers 90 F' held on the inner faces of the members C⁴ pivoted on the posts C³ of the foot section C, so as to permit of swinging the members C⁴ lengthwise along the bars C' to form the ends of the couch, as indicated 95 in Fig. 1, and to allow of swinging the said members into transverse position against the cross bar C², to form the foot board of the bed, as illustrated in Figs. 2 and 5. When the members C⁴ are in longitudinal position, as indicated in Fig. 3, they are fastened at their free ends to the head board A² by suitable fastening devices G, such as a hook and eye, as indicated in Figs. 1 and 4.

The head board A² of the head section A is provided on top with an extension H hav-

ing dowel pins H' engaging corresponding recesses in the top of the head board A². The extension H is adapted to form the front of the couch, and for this purpose the 5 posts C³ of the foot section C are provided with vertical guideways C⁵ for receiving the extension H, as indicated in Fig. 1, the dowel pins H' then resting on the floor.

When the parts A, B and C are extended 10 as illustrated in Figs. 2 and 5, and the bed spring sections D and D² are extended in a horizontal direction, and the cross bars D⁵ and D⁶ engage the keepers F, F', then the parts are held locked in place, that is to say, 15 cannot be further extended or folded, as the extended bed spring prevents longitudinal movement in either direction. When the parts are in the extended position, the members C⁴ extend transversely, so that the 20 keepers F' are at the inside and are engaged by the cross piece D⁶ of the bed spring section D². The middle section D' of the bed spring is permanently attached by the pivots D³ to the middle frame section B, and the 25 said middle section D' of the bed spring has its frame reinforced by cross bars D⁷ extending downward into the box B², as indicated in Fig. 5. The sections E, E' and the two sections E² are then placed in position 30 on the extended bed spring so as to form a mattress for the bed.

When it is desired to convert the extended bed into a couch, the sections E, E' and E² are first removed from the bed 35 spring and then the bed spring section D² is swung upward and folded onto the top of the middle bed spring section D', it being understood that in doing so the cross bar D⁶ disengages the keepers F', to unlock the 40 members C⁴ and thus permit of swinging the same around through an arc of 270°, to extend lengthwise of the bed for forming the ends of the couch, as shown in Fig. 1. The foot section C is now moved lengthwise 45 toward the middle section D' until the posts C³ abut against the lower ends of the sides B'. The end section D of the bed spring is now swung upward into an approximately vertical position, and in doing 50 so its end rail D⁵ disengages the keepers F to permit of sliding the head section A toward the middle section B, and then the members C⁴ are fastened by the fastening devices G to the head board A² of the head section A, to lock the folded sections together. The extension H of the head board A² is then removed and engaged with the 55 vertical guideways C⁵ so as to form the front of the couch. The section E is now placed in vertical position against the bed spring section D to form the upholstered back of the couch, while the section E' is placed on top of the bed spring section D² to form the seat of the couch, as indicated 60 in Fig. 1.

From the foregoing it will be seen that the piece of furniture can be quickly and conveniently converted from a couch to a bed and vice versa, and the bed clothes can be readily stored in the box B² when the 70 piece of furniture is used as a couch, it being understood that access to the box B² can be had at the time the bed spring section D² is folded upon the section D', and can be swung upward with the latter into open 75 position, turning with the pivots D³ to permit of placing the bedclothes into the box B², after which the sections D' and D² are swung downward to normal position.

Having thus described my invention, I 80 claim as new and desire to secure by Letters Patent:

1. A convertible couch and bed comprising a plurality of sections slidable one upon the other, one of the sections having pivoted 85 members adapted to be swung lengthwise of the bed to form the ends of the couch or transverse of the bed to form a foot-board.

2. A convertible couch and bed having a frame formed of a head section, a middle 90 section and a foot section, the said head and foot sections being mounted to slide lengthwise on the said middle section toward or from each other to form a frame for the couch or a frame for the bed, the said foot 95 section having movable members capable of forming the ends of the couch or the foot board of the bed.

3. A convertible couch and bed having a frame formed of a head section, a middle 100 section and a foot section, the said head and foot sections being mounted to slide lengthwise on the said middle section toward or from each other to form a frame for the couch or a frame for the bed, the said foot 105 section having movable members capable of forming the ends of the couch or the foot of the bed, and a spring made in connected sections capable of being extended to form a bed spring or being arranged to form the 110 spring back and spring seat for the couch.

4. A convertible couch and bed having a frame formed of a head section, a middle 115 section and a foot section, the said head and foot sections being mounted to slide lengthwise on the said middle section toward or from each other to form a frame for the couch or a frame for the bed, the said foot section having movable members capable of forming the ends of the couch or the foot 120 of the bed, and a spring consisting of a head section, middle section and foot section, the sections being pivotally connected with each other, the middle section being supported on the middle section of the frame, means on the said frame head section for supporting the free end of the said bed spring head section, and means on the said foot members for supporting the free end of the said bed 125 spring foot section.

5. A convertible couch and bed having a frame formed of a head section, a middle section and a foot section, the said head and foot sections being mounted to slide lengthwise on the said middle section toward or from each other to form a frame for the couch or a frame for the bed, the said foot section having movable members capable of forming the ends of the couch or the foot 10 of the bed, a spring made in connected sections capable of being extended to form a bed spring or being arranged to form the spring back and spring seat for the couch, and upholstered sections adapted to cover 15 the said spring when extended to form a mattress, one of the sections being adapted to form the couch back and the other the couch seat.

6. A convertible couch and bed having a frame formed of a head section, a middle section and a foot section, the said head and foot sections being mounted to slide lengthwise on the said middle section toward or from each other to form a frame for the couch or a frame for the bed, the said foot section having movable members capable of forming the ends of the couch or the foot of the bed, a spring made in connected sections capable of being extended to form a bed 25 spring or being arranged to form the spring back and spring seat for the couch, upholstered sections adapted to cover the said spring when extended to form a mattress, one of the sections being adapted to form the 30 couch back and the other the couch seat, and a storage chamber in the middle section below the middle bed spring section for receiving the bed clothes.

7. A convertible couch and bed provided with a frame formed of a middle section having two sets of longitudinal guideways, a head section having sides slideable in one of the said sets of guideways, a foot section having fixed sliding members slideable in the 45 other set of guideways, the foot section having pivoted members capable of forming the ends of the couch or the foot boards for the foot of the bed.

8. A convertible couch and bed provided with a frame formed of a middle section having two sets of longitudinal guideways, a head section having sides slideable in one of the said sets of guideways, a foot section having fixed sliding members slideable in 55 the other set of guideways, the foot section having pivoted members capable of forming the ends of the couch or the foot boards for the foot of the bed, supporting bars on the said head section and said pivoted members, 60 and a bed spring made in sections pivotally connected with each other, the middle section of the bed spring resting on and being

pivoted to the said middle frame section, and the free ends of the outer bed spring section being adapted to engage the said supporting bars. 65

9. A convertible couch and bed provided with a frame formed of a middle section having two sets of longitudinal guideways, a head section having sides slideable in one of the said sets of guideways, a foot section having fixed sliding members slideable in the other set of guideways, the foot section having pivoted members capable of forming the ends of the couch or the foot boards for the 70 foot of the bed, and the said foot section having a transverse guideway, and a head piece removably held on the said head section and adapted to engage the said guideway of the foot section to form the front 75 of the couch.

10. A convertible couch and bed provided with a frame formed of a middle section having two sets of longitudinal guideways, a head section having sides slideable in one of the said sets of guideways, a foot section having fixed sliding members slideable in the other set of guideways, the foot section having pivoted members capable of forming the ends of the couch or the foot boards for the 80 foot of the bed, supporting bars on the said head section and said pivoted members, a bed spring made in sections pivotally connected with each other, the middle section of the bed spring resting on and being pivoted to the said middle frame section and the free ends of the outer bed spring section being adapted to engage the said supporting bars, and a box on the said middle frame section below the said middle bed spring 85 section. 90

11. In a convertible couch and bed, a frame formed of three sections slideable one upon the other, and a spring formed of three pivotally connected sections, the end sections having interlocking engagement with the end sections of the frame. 105

12. A frame formed of a head section, a foot section, and an intermediate section upon which the head and foot sections slide, a spring formed of three sections pivoted together, the middle section being connected with the middle section of the frame by the pivot connecting it with the foot section of the spring, and interengaging means carried by the end sections of the frame and springs. 110

In testimony whereof I have signed my name to this specification in the presence of two subscribing witnesses.
